UNITED STATES PATENT OFFICE.

JACOB J. POMERANZ, OF BROOKLYN, NEW YORK.

DESIGN FOR A HINGE FOR AN EYEGLASS FRAME.

Application filed May 11, 1928. Serial No. 26,638. Term of patent 14 years.

To all whom it may concern:

Be it known that I, JACOB J. POMERANZ, a citizen of the United States, residing at Brooklyn, in the county of Kings and State of New York, have invented a new, original, and ornamental Design for Hinge for Eye-glass Frames, of which the following is a specification, reference being had to the accompanying drawings, forming part hereof.

In said drawings, Fig. 1 is a front elevation or face view of the hinge for an eye glass frame as mounted to connect the lens-

rim and temple of an eye-glass frame, said latter parts being shown in dotted outline; Fig. 2 is a side elevation of the same; Fig. 3 is a top edge elevation of the same; Fig. 4 is a rear face elevation of the same; and Fig. 5 is a rear side elevation of the same; said views showing my new design.

I claim:

The ornamental design for a hinge for an eyeglass frame as shown and described.

Dated May 2nd, 1928.

JACOB J. POMERANZ.
